United States Patent

Des. 239,346

Patented Mar. 30, 1976

239,346

ROTATABLE BOOK RACK OR SIMILAR ARTICLE

Robert K. Scherzer and Harold L. Hudson, Liverpool,
and Gregory G. Mt. Pleasant, Baldwinsville, N.Y.,
assignors to Gaylord Bros., Inc.

Filed Dec. 20, 1974, Ser. No. 534,877

Term of patent 14 years

Int. Cl. D6—04

U.S. Cl. D6—29

FIG. 1 is a perspective view of a rotatable book rack or similar article;

FIG. 2 is a front elevational view thereof;

FIG. 3 is a top plan view thereof;

FIG. 4 is a bottom view thereof; and

FIG. 5 is a cross-sectional view thereof taken along the line 5—5 of FIG. 2.

The front and rear elevational views are identical to the side elevational views.

We claim:

The ornamental design for a rotatable book rack or similar article, as shown and described.
